UNITED STATES PATENT OFFICE.

WILLIAM J. PHILIPS, OF PHILADELPHIA, PENNSYLVANIA.

ELECTRIC CABLE.

SPECIFICATION forming part of Letters Patent No. 252,249, dated January 10, 1882.

Application filed April 21, 1879. Patented in England, No. 1,475 of 1880.

To all whom it may concern:

Be it known that I, WILLIAM J. PHILIPS, of Philadelphia, in the county of Philadelphia and State of Pennsylvania, have invented certain new and useful Improvements in Electric Cables; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to an improvement in that class of telegraphic cables comprising two or more conducting-wires; and its object is to reduce retardation and interruption of the electric current by the inductive influence of the wires upon each other.

My invention is covered by British Letters Patent No. 1,475, A. D. 1880; and it consists, mainly, in a telegraph-cable composed of two or more conducting-wires proper, and an independent wire arranged between or centrally with respect to the said conducting-wires and out of contact therewith, said independent wire being provided with means for connection with the ground at points intermediate of the length of the cable. The independent wire is not connected with the direct conducting-wires of the cable at any point, nor with any other than ground terminals, and its office is to receive and conduct to the ground a portion of the currents induced by the cable-wires, said induced currents flowing over the independent or ground wire as the shortest route to an equilibrium, or that having least resistance of any conductor within the inductive influence of the said cable-wires.

In the accompanying drawings, Figure 1 represents a diametric section of a portion of a telegraphic cable constructed according to my invention. Fig. 2 is an end view of the same. Figs. 3, 4, and 5 respectively illustrate modes of forming the joint between two sections of cable.

Referring to Fig. 1, the letters A A indicate the ends of tubes inclosing the several wires, b, forming the direct conductors of a telegraphic cable, and a suitable insulating material surrounding and supporting said wires, which pro-

ject beyond the ends of the tubes to permit of splicing in the ordinary manner, as shown at c.

The letter D designates the independent wire which receives a portion of the inductive influence of the other wires and conducts the currents to the ground. This wire I prefer to locate in the center of the tube and equidistant from the other wires which surround it. As shown in Fig. 1, the ends of the independent wires D project somewhat beyond the ends of the tubes, and are provided at their tips, respectively, with right and left hand screws. These tips are connected by a sleeve, e, screw-threaded to correspond therewith, and having a projecting collar, f, which is also screw-threaded to receive the end of a ground-wire, g, the opposite end of which terminates in a ground-plate, h. This ground-wire g passes through a hole in a sleeve, I, which connects the two tubes A A, and when not applied is provided with an aperture, i.

The complete sections of cable may be manufactured by any of the known methods of making this class of cables, the arrangement of the wires being preferably as above described. In joining the ends of two sections of cable, as shown in Fig. 1, the sleeve I is first slipped upon one of the sections, and after the splicing and connecting of the wires is completed said sleeve is moved to embrace the ends of both sections, as shown, taking care that the lower hole in the sleeve I shall come in line with the screw-threaded collar f, projecting from the coupling-sleeve e. The ground-wire g is then inserted through the hole in the sleeve I, and its screw-threaded tip engaged with collar f. Care must be taken, of course, that the ground-wire g does not come in contact with any of the wires b. The connections having all been properly made, and the sleeve in proper position, it is thus firmly soldered, preferably with the ordinary plumbers' wipe-joints, and then is filled through the aperture i with molten insulating material similar to that used in the tube-sections. The aperture i and the hole through which the ground-wire passes are closely sealed by soldering and the joint is complete. Fig. 3 shows the sleeve I secured in place and the ground-wire in position for insertion.

Instead of using the screw-coupling for the

independent wire, this wire may be spliced in the same manner as the other wires. In this case the ground-wire must be connected with the independent wire by winding or coiling the former around the latter, and the free end of the ground-wire is then passed into the sleeve I, (which should be drawn partly off the tube for that purpose, as shown in Fig. 5,) and out through the hole therein. The sleeve I may be then moved to the position shown in dotted lines, the ground-wire drawn straight, as also shown by dots, the ground-plate attached, and the subsequent steps in forming the joint are the same as above described, as to the soldering and filling of the sleeve I with insulating material.

In the mode of joining the sections illustrated by Fig. 4, after the wires are all spliced and the ground-wire attached, a sleeve-like mold, which is composed of two semi-cylindrical parts and provided with a pouring aperture and an aperture formed by recesses in its edges to surround the ground-wire, is placed around the ends of the tube-sections and an insulator-joint molded. The mold is then removed, the insulator and adjacent ends of tubing wrapped with sheet-lead, as shown in section at s, Fig. 4, and another mold, one-half of which is shown at m, having an interior con-

30 cavity similar to the exterior shape of the sleeve I, Fig. 1, is placed around the joint. This mold is then filled with molten lead, and a solid joint is thus cast, connecting the two sections of tubing. The mold should be then removed. The sheet-lead s, it will be understood, is simply to protect the insulator-joint from being melted while the molten lead is

being poured in the mold. Instead of casting the lead joint, it may be "wiped" on, according to the practice of plumbers.

I do not confine myself to cables having in-
closing-tubes and fusible insulating material
surrounding the wires, as it is obvious that
ground-connections may be applied to an in-
dependent wire in any cable having two or
more direct conducting-wires, and the man-
ner of applying my invention will be suggested
by the circumstances and general character of
the cable in connection with which it is pro-
posed to be used.

What I claim is—

1. A telegraphic cable composed of two or
more conducting wires proper, and an inde-
pendent wire arranged between or centrally
with respect to the said conducting-wires and
out of contact therewith, said independent
wire being provided with means for connec-
tion with ground at points intermediate of the
length of the cable, as described.

2. The method substantially as described of
forming a lead joint for pipe sections and inter-
mediate mass of insulating material, the same
consisting in wrapping the ends of the pipe-
sections and intermediate insulating material
in foil and then casting molten lead around said
foil, substantially as described.

In testimony that I claim the foregoing I
have hereunto set my hand this 4th day of
April, 1879.

WILLIAM J. PHILIPS.
